Patented Mar. 30, 1915.

UNITED STATES PATENT OFFICE.

DOUGLAS E. GAINER AND WILLIAM L. STULL, OF BRUNSWICK, MARYLAND.

LUBRICATOR.

1,133,554.

Specification of Letters Patent.

Patented Mar. 30, 1915.

Application filed March 16, 1914. Serial No. 825,084.

To all whom it may concern:

Be it known that we, DOUGLAS E. GAINER and WILLIAM L. STULL, citizens of the United States, residing at Brunswick, in the county of Frederick and State of Maryland, have invented certain new and useful Improvements in Lubricators, of which the following is a specification, reference being had therein to the accompanying drawing.

10 This invention relates to lubricators and has for its object the production of a simple and efficient lubricator for use on locomotives and other parts of machinery which are desired or found necessary to lubricate.

15 Another object of this invention is the production of a simple and efficient means for forcing the lubricant from the lubricating cylinders and also for facilitating the returning of the forcing plungers to their 20 normal positions without the necessity of unthreading the plunger.

With these and other objects in view this invention consists of certain novel combinations, constructions, and arrangements of 25 parts as will be hereinafter fully described and claimed.

In the accompanying drawing:—Figure 1 is a top plan view of the lubricator. Fig. 2 is a section taken on line 2—2, of Fig. 1.

30 Fig. 3 is a top plan view of the central cylinder showing the manner in which the adjustable jaws are held in engagement with the threaded plunger. Fig. 4 is a section taken on line 4—4, of Fig. 3. Fig. 5 is a side elevation of the supporting bracket showing the manner in which the operating shaft is supported in engagement with the cylinders for feeding the lubricant. Fig. 6 is a section taken on line 6—6, of Fig. 1. Fig. 7 is

35 an enlarged perspective view of the pinion adapted to rotate the feeding gear. Fig. 8 is an enlarged section taken through the pinion illustrated in Fig. 7 showing the manner in which the fingers may be held in an inoperative position. Fig. 9 is a section taken on line 9—9, of Fig. 1. Fig. 10 is a section taken on line 10—10 of Fig. 2.

40 By referring to the drawings it will be seen that 1 designates the supporting base which is provided with a plurality of lubricant discharge pipes 2 leading from the respective lubricant cylinders. It should be understood that in connection with the present invention one or more cylinders may be

employed for accomplishing the desired 55 purpose, but for the purpose of illustration five cylinders have been shown, and it should be understood that these lubricant cylinders or receptacles may contain different forms of lubricant necessary to be fed to different 60 parts of the machinery, such as different parts of a locomotive or the like.

The base 1 supports a plurality of cylinders or receptacles 3 over which extends a cover plate 4. The plate 4 carries a plurality of 65 caps 4' which fit over the upper ends of the receptacle 3. The plate 4 also carries cap 5 which fits over the central cylinder 6, and this cap 5 is provided with a transversely extending channel portion 7 in which work 70 the slidably mounted thread carrying blocks 8. The plate 4 is hinged to the support 5' in order to allow the plate to be swung off of the receptacle 3. A latch 6' is also carried by the plate 4 for holding the plate 4 in 75 a set position. These blocks 8 are provided with laterally extending lugs 9 upon each side thereof, and these lugs 9 travel in the longitudinally extending slots 10 formed along the side of the channel portion 7 so 80 as to constitute a means for regulating the sliding movement of the thread carrying blocks 8. These thread carrying blocks 8 are adapted to engage the threaded pins 11, which pins carry the milled thumb heads 85 12 for the purpose of facilitating the rotation of the threaded pins 11 in order to move the thread carrying blocks 9 away from the threaded plunger 13 carried by the central receptacle or cylinder 5 as is illustrated in 90 Fig. 2. The inner faces of the thread carrying blocks 8 are threaded as indicated at 14, and it should be understood that these blocks may be drawn away from the threaded plunger 13 to allow the entire plunger to be 95 drawn vertically without the necessity of rotating the same in order to lift the plunger head 15 carried by the lower end of the plunger rod 13. The pins 11 extend beyond the side edge of the plate 4 as is illustrated 100 in Fig. 1.

A gear 16 is mounted upon an annular upstanding ring 17 carried upon the top of the plate 4, and this gear 16 is mounted upon the plunger 13 for moving the plunger 13 105 downwardly as the gear 16 is rotated. The gear 16 is provided with gear teeth 18 formed upon the upper face thereof, and

- these teeth are adapted to be engaged by the fingers 19 carried by the pinion 20. This pinion 20 is carried by a shaft 21, which shaft passes through a sleeve 22 carried by 5 the bracket 23. This bracket 23 may be supported upon the supporting plate 24 in any suitable manner so that the fingers 19 of the pinion 20 may efficiently rotate the gear wheel 16. The shaft 21 is provided 10 with a ratchet surface 25 which surface is engaged by means of the pawl 26 carried by the ratchet wheel 27. The ratchet wheel 27 is provided with diverging arms 28, which arms are adapted to be engaged by any suitable 15 operating means carried by the engine or machine with which the lubricator is co-operated. It should be understood that any suitable means may be employed for operating the ratchet wheel 27.
20. The shaft 21 is provided with a plurality of notch portions 29 upon the periphery thereof which notch portions are adapted to be engaged by the spring pressed plunger 30 mounted in the casing 31 so as to retard 25 the rotation of the shaft 21 at each quarter of a turn.

The pinion 20 comprises a substantially vertical body having substantially V-shaped pocket portions 32 formed along the periphery thereof. The gear fingers 19 are placed within the pocket portions 32 upon the supporting pins 33, which supporting pins are operated by means of the thumb nuts 34 in order that the fingers 19 may be thrown into the pockets 32 and held in such a position as to prevent the same from rotating the gear 18. By means of having the fingers 19 supported upon the pinion 21 in the manner as illustrated and described, 40 it should be understood that the feed of the lubricant from the cylinders 3 and 5 may be regulated for the reason that all of the fingers 19 can be thrown outwardly so as to have each finger rotate the gear 16 or move 45 the gear 16 the distance of four teeth at each revolution of the shaft 21. By having the fingers 19 capable of being withdrawn in the pinion 20, it will be seen that the pinion may be so regulated as to cause the 50 gear 16 to move either the distance of one, two, three, or four teeth at each revolution of the shaft 21.

The pinion 20 carries a spring pressed plunger 32' at the bottom of each socket 32 for the purpose of engaging the sockets formed upon the inner ends of the fingers 19. The plungers 32' will constitute an efficient means for holding the fingers 19 in a set position.

60. The threaded plunger 13 is provided with a longitudinally extending groove 35 which is engaged by a key 36 formed upon the gear wheel 16 so as to allow the plunger 35 to readily move downwardly as the gear 16

is rotated. The plunger 35 is provided with 65 a reduced end 37, and upon this reduced end 37 fits a spider frame 38 having a plurality of diverging arms 39. These diverging arms 39 carry downwardly extending plunger rods 40, which rods carry plunger heads 70 41 for working in the respective cylinders 3 and forcing the desired lubricant from the receptacles or cylinders as above described. A nut 42 is threaded upon the upper end of the plunger rod 13 so as to hold the spider 75 frame 38 in firm engagement with the plunger 13.

It should be understood that by having the ratchet wheel 27 mounted upon the shaft 21 in the manner described that the ratchet 80 wheel may be freely rotated in one direction without rotating the shaft 21, but when rotated in the opposite direction the shaft may be freely turned. It should be further understood that a very simple and efficient 85 means has been produced whereby the feeding plungers may be readily pulled to their normal position by the removal of the thread carrying blocks 8 out of engagement with the plunger rod 13.

90 As is illustrated in Fig. 2 the threaded plunger 13 is provided with a reduced portion 26' to allow the key carried by the driving gear to travel therein and rotate without operating the plunger 13.

95 Having thus described the invention what is claimed as new, is:—

1. A lubricator comprising a plurality of cylinders, a spider frame, a plunger rod supporting said spider frame, additional plunger rods suspended from said spider frame, an operating gear engaging one of said plunger rods, means for rotating said operating gear for feeding said plunger rods downwardly, and means for engaging said first mentioned plunger rod and adapted to be moved therefrom for facilitating the direct upward movement of said first mentioned plunger rod without the necessity of 100 rotating the same.

110 2. A device of the class described comprising a plurality of cylinders, an upstanding annular rim, a gear carried by said upstanding annular rim, a threaded plunger rod carried by said gear and adapted to be 115 threaded down as said gear is rotated, a spider frame carried by said plunger, said frame comprising a plurality of diverging arms, depending rods carried by said arms, plunger heads carried by said arms and also by said plunger, a cap supporting said threaded plunger, said cap provided with a transversely extending channel portion, said channel portion provided with longitudinally extending grooves upon each side 120 thereof, thread carrying blocks adjustably mounted within said channel portion, said thread carrying blocks provided with lat-

erally extending lugs working in said grooves, and means for engaging said thread carrying blocks for moving the same into and out of engagement with said threaded 5 plunger for facilitating the feeding of said plunger downwardly and also for facilitating the drawing of said plunger upwardly.

In testimony whereof we hereunto affix our signatures in presence of two witnesses.

DOUGLAS E. GAINER.
WILLIAM L. STULL.
